UNITED STATES PATENT OFFICE

STANLEY W. LAWTON, OF NEW YORK, N. Y.

HOLDER FOR COLLAPSIBLE TUBES

Application filed March 23, 1928, Serial No. 264,257. Renewed November 3, 1930.

My invention relates particularly to devices of the character set forth in my Patent 1,617,917 and my application 179,307, filed March 29, 1927, of which latter application 5 this present application is a continuation in part.

The principal object of my present invention is to simplify and cheapen the construction.

10 In its preferred form the casing is provided with a readily detachable front to facilitate access and the insertion and removal of compressible tubes. The compressing jaws are carried by a slide which is guided 15 in the casing, the latter being provided with integral flanges which serve as the guides. The jaws are operated by swinging bars which are so constructed and arranged that the finger levers may be connected directly 20 to the box. The tube is inserted between the jaws and has its nozzle or neck mounted in the bottom of the casing and closed by suitable means such as a spring pressed valve.

25 Fig. 1 is a perspective view of one form of device involving my invention.

Fig. 2 is a plan view and section on the plane of the line 2—2 of Fig. 6, showing the finger levers in full lines in the normal position of rest and in dotted lines showing 30 the position of the finger levers when the tube has been compressed.

Fig. 3 is a plan view and section on the plane of the line 3—3 of Fig. 6 showing the parts in the position in which the tube is 35 compressed.

Fig. 4 is a perspective view of the compressing jaws, the carrier slide and the swinging bars for operating them.

Fig. 5 is a front view of the device with 40 the front cover removed.

Fig. 6 is a vertical section and side elevation, the section being on the plane of the line 6—6 of Fig. 5.

Fig. 7 is a bottom view.

Fig. 8 is a fragmentary front view of the lower end with a modified form of closure.

The casing 10 is preferably formed of sheet metal, the back and sides being integral and provided with inwardly turned flanges 11. The top 12 and the bottom 13

may be secured in place in any suitable manner. The slide 14 carries the pivotal jaws 15 which are adapted to embrace the opposite sides of the tube 16 as shown in Fig. 5. The slide is U-shaped in plan view and the side 55 arms 17 fit the sides of the casing behind the flanges 11. Thus the walls and flanges of the casing form the guiding and supporting means for the slide 14.

The bowed spring 18 has its ends 19 engaged in recess or holes in the lower edges of the jaws so as to tend to spread the jaws apart, as shown in Figs. 4 and 5. The bars 20 are provided with upper and lower pivot studs 21 and 22 which engage in the top and 60 bottom plates 12 and 13. Finger levers 23 are secured directly to the upper ends of the bars 20 in any suitable manner. The pressure of the spring 18 tends to open up the 65 jaws and to press the bars 20 against the 70 flanges 11 when the parts are in the normal position of rest.

The bottom plate is provided with a funnel-like recess 24 with a mouth piece 25 adapted to receive the neck 26 of the tube 16. 75 This neck may be clamped in place by the thumb screw 27.

The closure 28 fits into the neck or nozzle of the tube so as to normally keep it closed. This closure is carried by a finger lever 29 80 which is pivoted at 30. The angular hub 31 is kept under pressure of the leaf spring 32 which tends to hold it in the closed position shown in full lines in Fig. 6 or in the dotted lines as shown in Fig. 6 when the tube is 85 open for use.

In Fig. 8 I have shown a modified form of closure 33 which has a spring pressed sleeve 34 mounted on the upright rod 35. This spring tends to keep the closure tight on its 90 seat. A finger piece 36 may be provided to facilitate lowering the closure 33 and turning it to one side so as to admit the brush to the outlet of the tube.

To operate the device the neck of the tube 95 is inserted in the mouth 25 and clamped in place by the screw 27, the upper end of the tube being inserted between the jaws 15 which are in their spread apart position. The weight of the slide and jaws is supported on 100

the tube itself. When it is desired to use the tube the closure 28 is dropped away from the outlet and the finger levers 23 are pressed toward each other by the operator. This pressure is transmitted through the bars 20 and through the outer lower edges of the jaws 15 which are thus pressed downwardly against the sides of the tube causing some of the contents to be ejected.

10 The teeth 37 tend to bite into the walls of the tube and press downwardly. When the pressure on the finger levers is released the spring 18 returns the parts to their normal position. The weight of the slide and jaws is sufficient to cause them to feed downwardly 15 slightly each time the tube has been compressed and the finger levers released.

20 The front or cover plate 38 has top and bottom flanges 39 and 40 which overlap the top and bottom plates of the casing. The sides are provided with inwardly pressed bosses 41 which are adapted to snap into recesses in the sides of the body of the casing to yieldingly hold the parts together. The upper 25 end of the front is provided with slots or openings 41 for the finger levers.

30 It should be understood that various changes in construction may be made without departing from the spirit or scope of my invention.

I claim:

1. A tube press, comprising a casing having side walls with inturned guide flanges, a slide guided in said casing by said flanges, 35 jaws pivoted to said guide, operating bars pivoted in the upper and lower ends of the casing, externally accessible operating means including finger levers and a removable front plate having top and bottom flanges co-acting 40 with the upper and lower ends of the casing, said removable cover plate having flanges provided with an interlocking engagement with the sides of the casing.

45 2. A tube press, comprising a casing having side walls, a slide guided in said casing, spaced jaws pivoted to said slide, swinging bars pivoted in the casing, externally accessible operating means including finger levers secured to said bars, and a removable cover 50 plate having flanges with an interlocking engagement with the sides of the casing.

55 3. A tube press, comprising a casing having side walls with guide flanges, a slide guided in said casing by said walls and flanges, jaws pivoted to said guide, operating bars coacting with said jaws, externally accessible operating means for said bars including finger levers and a removable front plate having top and bottom flanges co-acting with 60 the upper and lower ends of the casing.

65 4. A tube press, comprising a casing having side walls with inturned guide flanges, a slide guided in said casing by said walls and flanges, jaws pivoted to said guide, operating bars pivoted in the upper and lower

ends of the casing, and engaging said jaws and externally accessible operating means including finger levers connected to said bars.

5. A tube press comprising a casing having a means for supporting a compressible tube, a slide guided by the inner walls of the casing, tube compressing jaws hinged to said slide and movable therewith, a single spring carried by said jaws for normally separating the same and manually operable means for 75 operating said jaws.

6. A tube press comprising a casing, a slide guided in the casing, movable jaws carried by said slide and adapted to compress a tube, operating bars co-acting with said jaws 80 to compress the tube, and finger levers secured to the bars for operating said bars.

7. A tube press comprising a casing having a recess and a clamp screw for supporting a compressible tube, a slide guided by the inner walls of the casing, tube compressing jaws hinged to said slide and movable therewith, 85 bars for operating said jaws swingingly mounted in the casing and adapted to engage the jaws upon movement and means for 90 manually operating said bars.

8. A tube press comprising a casing, a slide guided in the casing, a pair of jaws hinged to said slide and adapted to compress a tube, bars hingedly mounted in said casing at opposite sides thereof co-acting with said jaws to compress the tube, and finger levers secured to said bars for operating said bars.

9. A tube press comprising a casing, means formed at one end of said casing for supporting a tube therein in upright position, means for compressing said tube slidably mounted in said casing, means for manually operating said compressing means and a single means for automatically retracting 100 said compressing means and operating means to inoperative positions upon the release of pressure upon said manually operated means.

10. A tube press comprising a casing adapted to support a tube therein, a pair of oppositely disposed jaws slidably mounted in said casing and adapted to compress said tube, means formed on said casing for guiding said jaws in their sliding movement, means for manually operating said compressing jaws 115 and a single means for automatically retracting said jaws away from said tube and said manually operated means away from said jaws.

11. A tube press comprising a casing adapted to support a tube therein, a pair of oppositely disposed jaws pivotally and slidably mounted in said casing and adapted to compress said tube, means formed on said casing for guiding said jaws in their sliding movement, bars pivotally mounted in said casing and adapted to engage said jaws upon rotation of said bars, levers fixed to said bars and extending exteriorly of said casing for 125 manually operating said bars and common 130

means for automatically retracting said jaws away from said tube and said levers away from said jaws upon the release of pressure from said bars.

- 5 12. A tube press comprising a casing adapted to support a tube therein, a pair of oppositely disposed jaws pivotally and slidably mounted in said casing and adapted to compress said tube, means formed in said casing for guiding said jaws in their sliding movement, bars pivotally mounted in said casing and adapted to engage said jaws upon rotation of said bars, levers fixed to said bars and extending exteriorly of said casing for 10 manually operating said bars and a spring carried by said jaws and normally urging said jaws away from each other, whereby said jaws are retracted from said tube and said bars from said jaws upon the release of pressure from the bars.

- 20 13. In a tube presser, a pair of pivoted jaws supported therein and pivoted at one of their ends, each jaw having a toothed surface adjacent the pivot end and a cam surface further removed from the pivot than said toothed surface and means for operating said jaws together to bring said toothed and cam surfaces to bear gradually upon the opposite sides of a tube.

- 25 14. A tube presser comprising a casing having an outlet at one end, means for supporting a tube in the casing with its nozzle at said outlet, a slide, means for guiding said slide in the casing, a pair of jaws pivotally carried by said slide and having surfaces for engaging and squeezing a tube between them and having arms, bars pivoted in the ends of the casing and extending longitudinally of the casing and having edges for pressing against the arms of the jaws, and finger levers connected to said bars and having portions extending outside of the casing for actuating the bars to move the jaws and compress the tube.
